UNITED STATES PATENT OFFICE

JOHN G. L. SKAR, OF JAMESTOWN, NEW YORK, ASSIGNOR TO ART METAL CONSTRUCTION COMPANY, OF JAMESTOWN, NEW YORK

FLOOR OR LIKE CONSTRUCTION

Application filed May 25, 1931. Serial No. 539,677.

This invention relates to floors or flooring and other building elements analogous in form, use or function to floors. Floors or flooring constructed in accordance with my invention are especially desirable for the galleries or platforms in library stack rooms and other structures where relatively narrow floors, platforms or the like are employed. In library stack rooms it is usual to provide galleries or platforms at suitable different elevations extending along the aisles between the shelving stacks to afford easy access to the shelves or parts of the stacks at different elevations. My invention is particularly applicable to such floors but it is not necessarily limited to floors for this purpose.

One object of the invention is to provide an improved floor or the like of novel construction.

Other objects of the invention are to provide a combined metal and concrete or plastic composition floor of novel construction; also to provide a floor which is of economical but strong, rigid and durable construction; which comprises a thin metal form in which the concrete or plastic tread material is molded and is constructed so that the metal form and concrete tread cooperate with each other to give strength and rigidity to the floor; which comprises a thin metal form in which a layer of tread material is confined and which forms a finished metal ceiling or bottom surface for the floor; in which the floor tread is formed of concrete or analogous plastic material molded and confined in thin metal forms which are adapted to be readily assembled on the floor supporting beams or members and form a permanent part of the floor and strengthen the concrete tread; in which the concrete or plastic material forming the tread of the floor is adapted to be molded in a sheet metal form which provides upwardly projecting curbs or guards at the edges of the floor that also function as strengthening or load-supporting members of the floor; and which has the other features of improvement and advantage hereinafter described and set forth in the claims.

In the accompanying drawings:

Fig. 1 is a transverse, sectional elevation of

a floor embodying my invention, illustrating the same as a gallery between library stacks.

Figs. 2 and 3 are longitudinal sectional elevations thereof on lines 2—2 and 3—3, respectively, Fig. 1.

Fig. 4 is a plan view of the floor showing a portion of the tread removed to disclose the underlying metal form.

10 represents floor-supporting beams or members which, in the library stack structure illustrated in the drawings, extend transversely across the aisles between two stacks of shelving 11. These beams may be a part of the skeleton frame structure of the shelving stacks, or may be floor or analogous supporting elements. The beams 10 shown are I-beams, but they may be of other form, but preferably are provided with oppositely projecting, horizontal top flanges 12. Supported by the beams and extending lengthwise of the aisle, transversely of the floor beams 10, is a metal form or flooring structure preferably composed of similar sections, each extending from one floor beam 10 to the next and resting at its opposite ends on the tops of adjacent beams, the several sections of this form being arranged end to end, or with their ends contiguous or abutting above the beams 10. Each section of this metal form is preferably made of a sheet metal 15 plate bent to form a horizontal bottom 13, upturned side edge flanges 14 and upturned end flanges 15. The side flanges 14 are preferably formed with rebent or downwardly and inwardly extending, inclined margins or 20 portions 16. These sections are adapted to be secured in place end to end on the floor beams 10 in any suitable manner, as for instance, by means of bolts 17 extending through the top flanges of the beams and through the overlying end portions of the bottoms 13 of the form sections. The metal form-sections thus arranged, form a continuous, shallow, metal trough or form having upstanding side 25 guards or flanges.

Within the metal form or trough thus constructed is a layer of material 18 which forms the tread of the floor. This tread is preferably made of concrete or a plastic composition adapted to be spread or molded in

the metal form or trough formed by the metal sections 13. In the case of a concrete floor tread for example, the concrete, while in suitably fluid condition, is poured or spread in the form or trough so as to form a relatively shallow layer of the concrete. Preferably the concrete layer is reinforced by mesh or other suitable metal bonding or reinforcing material 19 which is embedded in the 5 layer of concrete and serves the usual function of metal bonds or reinforcements in concrete structures. In erecting or constructing the floor, the several sections 13 of the metal trough are preferably secured 10 in position end to end on the beams 10 and then a layer of the concrete or tread material is placed or molded in the continuous trough formed by the trough sections so that the tread material is continuous across and covers 15 the joints between the several sections of the metal trough or form. Thus, while the metal form or trough is of sectional formation, the tread material is preferably continuous or extends without joints from end to 20 end of the floor.

When molding the tread material in the metal form or trough, the tread material is worked or forced into the grooves between the portions 14 and 16 of its side flanges of the 30 metal form or trough and the layer of tread material is made deep enough for the lower edges of the rebent portions 16 of the side flanges to be embedded in the body of the tread material. The side flanges thus confine 35 the tread material and the latter acts as a bond or tie between the upstanding curbs or flanges of the floor, so that the metal form or trough and the tread material mutually coact to form a strong, rigid floor which, 40 though of relative little vertical depth or thickness, has great supporting strength.

The end flanges 15 of the form or trough sections are also embedded in the tread material and thus act to prevent longitudinal 45 displacement of the tread material in the trough, while the material, when set, forms a strong bond between the sections of the metal form or trough. The flooring thus constructed, therefore, while it may be of relatively 50 small depth or thickness, nevertheless has great tensile and load supporting strength and rigidity both lengthwise and transversely of the floor.

In the construction shown, the bottom 55 plates of the metal form or trough sections are also bent to form a longitudinal conduit or recess 20 extending lengthwise of the trough, preferably midway between its side edges. This recess forms a conduit or compartment 60 extending lengthwise of the floor in which electrical conductors for lighting or other purposes can be enclosed by removable cover pieces 21. The cover pieces 21 shown are of channel shape cross section having 65 side flanges which extend into the con-

ductor conduit, and the ends of these cover pieces rest upon the tops of the floor beams 10. The conduit covers are thus adapted to be supported and retained in place by the floor beams. Preferably the cover pieces are made of such width that they fit snugly between the side walls of the conduit so that they have to be forced into place in the conduit, and the frictional engagement of the flanges with the side walls of the conduit assists in holding the covers in place. The bottom surfaces of the cover pieces 21 are preferably flush with or in the same plane as the bottom surfaces of the bottom plates of the form sections. 70 75 80

This channel shaped formation between the side edges of the form or trough also serves to stiffen the form or trough and cooperate with the relatively deep side flanges or curbs of the floor to prevent sagging or bending of the floor between the supporting beams 10. 85

In practice, the metal form or trough sections are fabricated in lengths suitable to the spacing of the floor beams or supports in the particular building or structure in which the floor is to be installed. The sections, thus made to size, can be quickly and easily placed and secured in position to complete the form, and it is a very practical and economical proceeding to spread the concrete or tread material in this metal form. The floor constructed as described possesses the further advantage of providing a finished metal ceiling 90 95 100 on its underside.

I claim:

1. A floor or the like comprising a trough-like metal form having upstanding side flanges and a layer of tread material arranged in said form on the bottom thereof and confined by the side flanges of said form, the side flanges of said metal form projecting above the tread material and forming upwardly projecting side curbs for said floor. 105

2. A floor or the like comprising a thin metal form having an upstanding side flange with a downwardly extending marginal portion, and a layer of tread material confined in said form, said side flanges projecting above the tread material and the marginal portion of said flange being embedded in said tread layer. 110 115

3. A floor comprising a thin metal form having opposite upwardly projecting side flanges with inwardly and downwardly extending marginal portions, and a layer of tread material confined within said form between said side flanges and extending into the grooves between the upwardly and downwardly extending portions of said side flanges, and said side flanges forming curbs projecting above said tread material. 120 125

4. A floor or the like comprising a metal form composed of sections arranged end to end and having upstanding flanges at op- 130

posite side edges of said sections, and up-standing flanges at the end edges of said sections, and tread material confined in said form by said flanges and extending over said 5 end flanges and continuously across the joints between said form sections.

5. A floor or the like comprising a metal form composed of sections arranged end to end and having upstanding flanges at opposite 10 side edges of the sections and tread material confined in said form by said flanges and extending continuously across the joints between said form sections, said form sections having flanges at their adjacent end edges 15 embedded in the tread layer.

6. A floor or the like comprising metal plates arranged end to end and having up-turned flanges at their meeting ends, and a continuous layer of concrete material supported 20 on said plates and extending over said flanged ends and across the joints between said end flanges, means for supporting said plates at their adjacent flanged ends, said plates having also upturned flanges at 25 their side edges and stiffening reinforcements extending lengthwise of the plates between said side flanges and projecting upwardly from the plates into said concrete layer.

7. The combination of spaced floor supports, a floor comprising a trough-like metal form composed of sections arranged end to end and resting at their ends on said supports, said sections having upstanding side flanges and upstanding end flanges, and a 30 layer of concrete tread material confined in said form between the side flanges thereof, and having the end flanges of said form sections embedded in said material.

8. The combination of spaced beams, thin 35 metal plates arranged end to end and each extending from one to another of the beams and being supported thereby, said plates having reinforcing portions which extend transversely of the beams and stiffen 40 the plates between the beams, and concrete material held on said plates by portions thereof and covering the joints between said plates, said plates having side flanges 45 projecting above said concrete material and forming raised curbs at the sides thereof.

9. A floor or the like comprising thin metal plates arranged end to end and supported at their ends, said plates being stiffened between the end supports by a downwardly opening 50 longitudinal channel between their side edges, and a layer of tread material secured on said plates and crossing the joints between the plates.

JOHN G. L. SKAR.
